SEWING MACHINE ATTACHMENT

Howard C. Underwood, New York, N. Y.

Application November 12, 1934, Serial No. 752,593

5 Claims. (Cl. 112—152)

This invention relates to an improved attachment for sewing machines, and more particularly to a duplex gauge.

Among the principal objects which the present invention has in view are: To provide improved means for guiding work with respect to a pair of needles; for variably guiding stitching with respect to an edge of said work; to enable the stitching to be sloped toward the edge and closer than normal to a part of said edge; to attach the means to a sewing machine at a place thereof which will not interfere with the normal operation of the machine; to be enabled to operate the means when desired without stopping the machine or continuity of the lines of stitching, and to obtain other advantages and results as may be brought out in the following description.

Drawing:

Figure 1 is a plan view of part of a sewing machine and showing my improved attachment thereon;

Figure 2 is a longitudinal sectional view of the same shown as taken on line 2—2 of Figure 1;

Figure 3 is a perspective view of the attachment and a portion of a garment and showing the attachment before operation;

Figure 4 is a similar view and showing the attachment in operation; and

Figures 5 and 6 are portions of the article in completed condition.

Description:

As seen in the drawing, I have shown a part of a sewing machine 10 having a throat plate 11, feed dog 12, presser foot 13 and a plurality of needle openings 13' in the presser foot 13. The parts just mentioned may be conveniently attached as usual as heretofore to the sewing machine structure which includes a bed 14 as will be readily understood by those skilled in the art. The present invention is particularly directed for applying a double line of stitches to an article requiring the same and which may also require a finishing touch of a strip of binding, such as tape or the like, to be secured to the hem edges, as occurs in the manufacture of a collar or the like. Attention is especially called to the fact that the corner points or tips of semi-soft collars, as usually worn by men, often become damaged through laundering because the stitches as applied heretofore in collar construction are not close enough to the outside edge of the same, and it is to overcome this defect in the prior art that the present invention is more particularly directed.

In carrying out the invention and referring

more particularly to Figures 1 to 4 inclusive, I have shown my improved attachment as including an elongated arm 15 projecting forwardly toward the operator to be conveniently operated by hand when desired. Said arm may be conveniently and suitably attached at one end to a plate 16 as by a bolt 17 and free to move in either direction. The pivoted end of the arm is shaped to be a cam 18 which abuts against an end directed toward the cam of a sliding rod 19. The rod may conveniently slide within a housing 20 of a bracket 21. Said housing has a longitudinal slot 22 centrally therein through which projects an upstanding post 22', preferably integral with the rod, said slot preferably limiting the forward or backward movement of the rod when in operation.

The outside end of the rod 19, that is, the end opposite from the end juxtaposed to the cam 18, likewise projects upwardly, as at 23, and comprises a movable work gauge which will contact the edge of an article being stitched.

In operation, a binding or tape 24 employed in completing the preferred construction of the collar is sewn to the article by virtue of a pair of needles 25. The tape 24 for neatness of the article is preferably sewn on the inside or wrong-side of the article to more securely retain the hems along the fold lines as seen in Figures 2 and 6, and more fully shown and described in my co-pending application, Serial No. 749,190 filed October 20, 1934. Referring now to Figure 2, it will be noted that the tape 24 is fed through the feed dog 12 as far as the needle openings where the tape issues onto the top of the feed dog and the needles 25 securely sew the tape to the underside or wrongside of the article or collar 26.

In applying the double line of stitches 27 to the tape 24 and collar 26 along the edge of the collar, it will be noted that the stitching is in parallel relationship and parallel to and spaced normally from the edge of the collar throughout the hem except at the corner point. Since it is desirable to protect the corner point and to prevent the point from becoming distorted, the arm 15 is swung towards the left as in Figure 4, whereby the cam 18 engages the sliding rod 19, pushing the same towards the edge of the collar 26.

By virtue of the upstanding end or gauge 23 of the rod 19, pressure is exerted upon the edge of the collar 26 or other work, sliding the work so that the edge next the lines of stitching moves closer to the needles 25. Preferably the pressure is applied gradually and the machine slowed down

by the operator as the stitching continues thereby causing the lines of stitching to converge or slope toward the edge of the collar. When the gauge reaches its innermost position toward the 5 needles, the lines of stitches again continue parallel to the edge, but closer thereto than normal, wherein the lines of stitches are shown tapering gradually and then resuming their parallelism with the edge of the collar, but closer there- 10 to. As the lines of stitching are thus made very close to the edge of the collar 26 or other work in proximity to the tip or corner point, the point is properly secured and prevented from unseemly distortion, such as has been heretofore preva- 15 lant with collars or the like, particularly after being laundered. The operator may swing the work to continue sewing upon the intersecting edge and preferably the gauge 23 is left so that the initial part of the lines of stitching begin- 20 ning from the point will be closer than normal to the edge, and after a few stitches have been made, the arm 15 is returned slowly to its initial position, thereby returning the lines of stitching to normal distance and parallelism to the 25 edge of the collar.

As best shown in Figures 1, 3 and 4, the sliding rod 19 is held in engagement with the edge of the cam 18 by means of a spring 28 suitably attached to the upstanding post 22' of the sliding rod and 30 at its other end to a pin 29 on bracket 21. The arm 15 is adjustably stopped at proper angular displacements determined in adjusting the attachment upon the machine to secure the proper spacing of the stitching from the edge of the 35 work. Convenient stops for this purpose are indicated as a pair of spaced screws 30 pointing towards each other and the arm 15 such that one screw, that is, the one nearest the needles 25 will function to determine the spacing of the 40 stitching closest to the edge of the work and the other screw, that is, the one furthest from the needles, will function to adjustably limit the spacing of the lines of stitching in its normal distance from the edge.

45 The material comprising the collar blank being of multi-ply woven fabric is subject to injury and distortion by rapidly operating needles 25 stitching the tape 24 to the hem edges of the collar 26 when too close to the edge and one deleterious effect resulting is that the cross-threads of the fabric are caused to project outwardly beyond the edge of the finished collar making it rough or ragged. To eliminate this bad feature, I have found it advantageous to run the lines of 50 stitches 27 back from the edge a distance herein referred to as normal, so should there be an accidental break in the cross-threads of the fabric, sufficient material will remain along the edge for preventing a possibility of such broken threads 55 projecting outwardly beyond the said edge.

As the needles 25 come closer to the tips or corner points, the machine is gradually slowed down and the gauge 23 applied to bring the edge of the collar 26 closer to the path of the needles 60 thereby applying the stitches adjacent the edge of the tips or corner points as heretofore described. Since the machine has been slowed down considerably, the needles will enter the fabric at a lower rate of speed under which conditions they do not tend to break the cross-threads of the fabric. After the one side edge of the corner point has been stitched, the operator may then swing the collar to a proper position whereby the other edge may be stitched. The machine 65 continues to be run slowly until the corner point 70

is completed, after which the gauge is released to normal position and the lines of stitches applied further in from the edge and at a greater speed. The slowing down of the machine is a usual operation when sewing at corner points, 5 and is not especially done for manufacture of a collar according to the present invention. I, therefore, utilize the usual slowing down of the machine to enable me to then bring the lines of stitching closer to the edge according to the advantages above explained and constituting an important feature of this invention. 10

By use of the present invention, a collar or the like can be manufactured with great rapidity with the lines of stitching throughout the major portion of the margins of the collar having a normal spacing from the edge both for security and for purposes of appearance, and the lines of stitching may be brought to a much closer spacing from the edge adjacent the tips or corner points of the collar with ease and a minimum requirement of skill upon the part of the operator with assurance that the stitching will be run upon the collar and not inadvertently run off before the extreme point is reached. 25

I claim:

1. A sewing machine attachment as characterized comprising a guide operable during and without interruption of the stitching operation for adjusting the edge of the work at a variable 30 distance from the lines of stitching, a pivoted arm abutting one end of said guide and projecting toward the operator for shifting the guide from one position to another, and means on either side of said pivoted arm adapted to adjustably limit the amplitude of swing of said arm. 35

2. A sewing machine attachment as characterized comprising a guide providing a rod slidable toward and away from the work operable during and without interruption of the stitching operation for adjusting the edge of the work at a variable distance from the lines of stitching, a pivoted arm adjacent the rod projecting toward the operator, said arm having a cam abutting one end of the guide and for shifting said guide 45 from one position to another, said rod having an upstanding post approximately midway thereof, and a coil spring, one end of which is attached to said post for maintaining the end of the rod furthest from the work in engagement with said 50 cam, and adjustable means adjacent the arm for limiting the amplitude of swing of said arm thereby cooperating with the said coil spring to limit the movement of said rod.

3. A sewing machine attachment as characterized comprising a plate with a bracket having a housing, said housing providing a rod slidable toward and away from the work operable during and without interruption of the stitching operation, said rod at its end nearest the work having 60 an upwardly projecting portion for contacting the edge of the work and adjusting the same at a variable distance from the lines of stitching, an arm pivotally attached to the plate and projecting toward the operator, said arm having a cam contacting the other end of the slidable rod for shifting the said upwardly projecting portion of the rod from one position to another, said housing having an opening midway thereof, the slid- 65 able rod having means projecting upwardly through said opening, said means retaining one end of a coil spring thereon, and a second means on the bracket for retaining the other end of the spring whereby the end of the rod furthest 70

from the work is maintained in engagement with the cam.

4. A sewing machine attachment as characterized comprising a plate with a bracket having a housing, said housing providing a rod slidable toward and away from the work operable during and without interruption of the stitching operation, said rod at its end nearest the work having an upwardly projecting portion for contacting the edge of the work and adjusting the same at a variable distance from the lines of stitching, an arm pivotally attached to the plate and projecting toward the operator, said arm having a cam contacting the other end of the slidable rod for shifting the said upwardly projecting portion of the rod from one position to another, said housing having an opening midway thereof, the slidable rod having means projecting upwardly through said opening, said means retaining one end of a coil spring thereon, and a second means on the bracket for retaining the other end of the spring whereby the end of the rod furthest from the work is maintained in engagement with the cam, and said bracket and plate having adjusting means for limiting the thrust of the said arm during operation.

5. A sewing machine attachment as characterized comprising a plate with a bracket having a

housing, said housing providing a rod slidable toward and away from the work operable during and without interruption of the stitching operation, said rod at its end nearest the work having an upwardly projecting portion for contacting the edge of the work and adjusting the same at a variable distance from the lines of stitching, an arm pivotally attached to the plate and projecting toward the operator, said arm having a cam contacting the other end of the slidable rod for shifting the said upwardly projecting portion of the rod from one position to another, said housing having an opening midway thereof, the slidable rod having means projecting upwardly through said opening, said means retaining one end of a coil spring thereon, and a second means on the bracket for retaining the other end of the spring whereby the end of the rod furthest from the work is maintained in engagement with the cam, and said bracket and plate having adjusting means for limiting the thrust of the said arm during operation, said adjusting means comprising a pair of spaced screws facing each other whereby the arm when directed towards the one screw the lines of stitching will appear closer to the edge of the work than when the arm is directed towards the other screw.
